UNITED STATES PATENT OFFICE.

KENNETH DAVIS, OF ST. BENEDICT, PENNSYLVANIA, ASSIGNOR TO REMBRANDT PEALE, OF NEW YORK, N. Y.

MATERIAL-CONVEYING MECHANISM.

Application filed January 21, 1920. Serial No. 352,928.

To all whom it may concern:

Be it known that I, KENNETH DAVIS, a citizen of the United States, residing at St. Benedict, Pennsylvania, have invented certain new and useful Improvements in Material-Conveying Mechanism, of which the following is a specification.

The invention relates to conveying mechanisms, and more particularly to a novel conveying mechanism for transporting loose material in bulk, and in certain features thereof, the invention relates to such a conveying mechanism operating on a slope or gradient.

Objects and advantages of the invention will be set forth in part hereinafter, and in part will be obvious herefrom, or may be learned through practice with the invention; said objects and advantages being realized and attained through the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a general elevation of a mechanism constructed in accordance with the invention, and applied in an exemplary manner to conveying coal up a mine slope;

Fig. 2 is a fragmentary elevation, on a larger scale, of a part of the material conveying mechanism shown in a general way in Fig. 1;

Fig. 3 is a top plan view corresponding to Fig. 2;

Fig. 4 is a vertical, transverse section taken substantially on line 4—4 of Fig. 2;

Fig. 5 is a vertical, longitudinal section taken substantially on line 5—5 of Fig. 3;

Figs. 6 and 7 are views similar to Fig. 5, but with parts omitted, showing the operation of the mechanism in conveying material;

Fig. 8 is an enlarged detail of one of the devices for fastening the sections of the conveyor together;

Fig. 9 is an enlarged plan view of the actuating mechanism for the conveyor, said mechanism being shown in a general way in Fig. 1;

Fig. 10 is a side elevation of the actuating mechanism shown in Fig. 9;

Fig. 11 is an elevation of different form of actuating mechanism for the conveyor;

Fig. 12 is a fragmentary plan view, on an enlarged scale of the automatic reversing mechanism for the actuating mechanism shown in Fig. 11;

Fig. 13 is a general elevation of a form of the conveyor for transporting material down grade;

Fig. 14 is a similar view to Fig. 13, but showing a somewhat different form of the mechanism;

Fig. 15 is a vertical, transverse section, on an enlarged scale, taken on line 15—15 of Fig. 14;

Fig. 16 is an enlarged fragmentary detail, in elevation, of the construction shown in the central part of Fig. 14;

Fig. 17 is an elevation of a form of driving or actuating mechanism for the conveyors shown in Figs. 13 and 14;

Fig. 18 is an enlarged fragmentary end elevation of the mechanism shown in Fig. 17;

Fig. 19 is an elevation of a different form of actuating or driving mechanism for the conveyors shown in Figs. 13 and 14; and

Fig. 20 is a fragmentary detail of the winding drum shown in Fig. 18 and of the reversing mechanism therefor;

Fig. 21 is a fragmentary, partly diagrammatic plan, showing the drive of Fig. 10 adapted to the conveyor of Fig. 14, as an alternative for the drive of Fig. 17.

The invention has in view providing a mechanism for rapidly, easily and economically handling loose or broken materials, such as coal, stone or the like, which is conveyed loosely or in bulk. Objects of the invention in part are to provide for the economical handling of such material; to provide for practically automatic handling thereof, requiring little or no labor by workmen; to avoid the employment and handling of cars, including the loading, handling, and especially the dumping thereof; to provide for immediate handling of the material ir-

55

respective of variations in the volume or bulk of material which is supplied at different times.

In certain aspects or applications of the invention, it is designed for the conveyance of loose material or materials on a slope or gradient. The conveyor in such cases is divided longitudinally into two or more parts, and means are provided whereby the weight of a portion of the downwardly traveling material, that is, the material traveling downwardly with one part of the mechanism, is made to counterbalance or raise another part of the mechanism, which is traveling upwardly. Having in view the objects and conditions outlined above, such counterbalancing shifts alternately from one portion of the material and mechanism to another in succession, thereby effecting a great saving in the work or horse power required. Other objects and advantages will be pointed out in connection with the particular description of various mechanisms or parts, or will be obvious from such a description, or will be learned through practice with the invention.

Referring generally to the illustrative embodiment of the accompanying drawings, a conduit or trough is provided for holding and traveling the loose material, the conduit or conveyor trough reciprocating to and fro, there being within the conduit or trough spaced apart members operating to permit the material within the conduit or trough to travel therewith in one direction, but holding the material against movement with the conduit or trough in the opposite direction. The conduit or conveyor itself preferably consists of a series of sections detachably attached together, the conveyor reciprocating to and fro along a guideway, which is preferably a track whereon pairs of wheels upon which the conduit sections are mounted run.

The spaced apart members within the conveyor trough are preferably blades arranged across the trough, pivotally mounted in stationary position, and equally spaced apart, but swingable to permit the above-described action of the blade upon the conveyed material, the pivoted blades being preferably in an inclined position within the trough. Also it is preferable to have the path of reciprocation of the conduit or conveyor trough somewhat greater than the distance between the spaced apart blades.

In the application of the invention to conveying materials upon a gradient or incline, in one aspect of the invention the conduit or conveyor trough is counterbalanced, so that the work expended is substantially that required for the elevation of the material plus the relatively small amount of frictional loss. Where the mechanism is utilized for conveying the material downwardly on

an incline or gradient, the counterbalance is not employed, as the invention in its preferred form provides, as already explained, for utilizing the weight or gravitational action of one part of the descending mechanism and contained material in forwarding or advancing another part of the mechanism, this action successively alternating between two or more different parts of the traveling mechanisms and descending material. 70 75

Referring now in detail to the embodiment of the accompanying drawings:

Fig. 1 is a general elevation, more or less diagrammatic, of the exemplary application 80 of the invention to conveying upwardly coal or other loose material along a mine slope, and

Figs. 2 to 12 included are details of the construction and operation of a mechanism such as is shown in Fig. 1. Figs. 13 and 14 are elevations, likewise partly diagrammatic, of the application of the invention to the conveyance of loose material down a gradient or incline, and Figs. 15 to 20 are detailed views showing in an exemplary way the operation of such a mechanism. 85 90

Referring now to Fig. 1 and the above-mentioned accompanying group of figures, the conduit or conveyor trough is shown consisting of a plurality of sections 1, each section comprising vertical sides 2 and 3 and a bottom 4, the top and the ends of these conduit or conveyor sections being open. The sections are connected together by attachable and detachable devices, and as embodied, hooks 6 are shown having, respectively, pivot mountings 7, upon both sides of a conduit section at one end thereof, and hooking, respectively, over pins or hooks 8, fixed to the side walls of the adjacent end of the adjoining section. There are also preferably hooks for connecting together the bottom frames of the sections, and these will be later described. The conduit or conveyor trough sections are offset at one end, so that one end of each section will fit neatly within the adjacent end of the next adjoining section, as shown at 9 in Fig. 3. 100 105 110

The conveyor sections are preferably provided with bottom frames, which may be rectangular in shape and may conveniently consist of channel beams. As shown, such a frame has end reaches 11 and 12 and side reaches 13 and 14. The fastening device for the frames, when employed, may consist of a hook 15 pivoted at 16 to one of the cross reaches 11 of the bottom frame of one section and hooking about a bent pin 17 in the cross reach 12 of the bottom frame of the next adjacent section. A locking pin 18 may be passed through the flange of the channel 12 to hold the hook 15 in position. 120 125

As stated, the conveyor or conduit recipro-

- cates to and fro along the guideway, and there are preferably provided wheels on each conveyor section running upon trackways. With this in view, and as embodied, 5 each section is provided with two pairs of wheels 20 and 21, each pair being mounted, respectively, on an axle 22, the axle passing through the frame members 13 and 14, and preferably through bearing blocks 24 and 10 25 fixed within the channel beams. Track rails 26 and 27 are provided, which are shown of the usual T rail form, the wheels being likewise shown as the ordinary flanged track wheels.
- 15 The counter balance may be of any convenient or standard form, and in Fig. 1 there is shown a counter-balancing weight 30, connected to a cable 31 which is also connected to the upper end of the train of conveyor trough or conduit sections, and runs over one or more sheaves 32.
- The embodied form of devices for effecting the progression or travel of the loose material, such as coal, along and within the 20 conveyor, comprises a plurality of spaced apart blades 35, located within the conveyor or conduit, and disposed across it and substantially filling the cross section of the conduit with fair or easy clearance. The blades 25 are regularly spaced apart, and are stationary considered longitudinally of the conveyor, but are pivotally mounted, that is, are swingable along the conduit. The blades 30 35 are preferably inclined, as shown in Figs. 1 and 5 whereby they will permit the loose, broken material lying in the conduit to pass therebeneath in one direction (toward the left in Figs. 1 and 5), but will hold the material against movement with the conduit in the opposite direction (to the right in Figs. 1 and 5). The blades 35 are preferably provided with baffles 36 to prevent the material piling upwardly and backwardly over the blades. The various blades 35 are respectively mounted on a pair of arms 37 and 38 pivotally or swingably journaled on a cross rod 39. The rods 39 are supported in any suitable manner, and in Fig. 4 one rod 39 is shown with its ends resting in supporting journal brackets 40 and 41, which are fastened, respectively, upon posts 42 and 43, which may conveniently be a part of the mine timbers when the mechanism is installed in the mine. If desired 45 any suitable stops 44 may be employed to prevent too great pressure of blades 35 against the conveyor bottom 4, and thereby causing unnecessary friction.
- Suitable actuating means are provided for moving the conduit or conveyor train to and fro in its reciprocatory travel along the tracks, and as embodied, a cross rod 50 is fixed to the bottom frame of one of the conduit sections. Pivotally mounted thereon is 50 55 a connecting rod 51, the other end of such connecting rod being pivotally mounted upon a cross rod 52. The cross rod 52 is connected at its ends to two endless sprocket chains 53 and 54. The sprocket chains 53 and 54 run respectively over idler sprocket 70 wheels 55 and 56, and also over driven sprocket wheels 57 and 58. Fixed on the shaft 59 of sprocket wheel 57 is a gear 60. Fixed on the shaft 61 of sprocket wheel 58 is a gear 63. The gears 60 and 63 mesh respectively with pinions 64 and 65 which are fixed on a shaft 66. Fixed on the shaft 66 is a gear 67, and meshing with the gear 67 is a pinion 68, which is fixed on the shaft of a motor 69. The bearings for the sprocket 80 wheels are on the outside to give clearness for cross rod 52. Suitable guides for the sprocket chains to prevent sagging, or other deflection may be provided if desired in the usual manner.
- In the illustrative embodiment of Fig. 1, showing the conveyance of material up a mine slope or other incline, a receiving chute 70 is shown, into which is emptied the material delivered at the upper end of the 85 conduit. The material passes from thence into a car 71. It will be understood that any usual weighing devices, screening and picking devices, or other apparatus or mechanism may be employed at this point, but the description and showing thereof are unnecessary, as they are well known. At the bottom end of the conduit a car 72 is shown being dumped into the conduit, and at 73 another conduit system is shown conventionally as emptying into the inclined 90 conduit.
- The manner of operation of the mechanism just described is briefly as follows (the further details thereof being clearly understandable from the preceding description) :—
- The motor 69 drives the sprocket chains 53 and 54, and through the connection rod 51 the train of conduit sections 1 is reciprocated to and fro on the tracks 26 and 27. The blades 35 will swing upwardly, and permit the loose material lying in the conduit to travel with the conduit and beneath the blades during the travel of the conduit to the left in Figs. 1, 5 and 7, and as shown in Fig. 5. On the travel of the conduit in the opposite direction the blades hold the material from traveling backwardly with the 100 conduit.
- The distance or spacing apart of the blades and the distance or length of the longitudinal reciprocatory travel of the conduit are so related or relatively proportioned 105 that the mass of material behind one blade is left in such position that during the reverse travel of the conduit (to the left in Figs. 5, 6 and 7) said mass of material is carried forward under the next blade to a point beyond said next blade. Thus said blade is 110 115 120 125 130

well behind this particular mass of material and in position to hold it during the next reverse reciprocation of the conduit (to the right in Figs. 5, 6 and 7). Thus the material is conveyed along the conduit on each reciprocation thereof. The weight of the reciprocating conduit is practically neutralized by the counter balance 30, the greater part of the work expended going into the upward movement of the material.

With the mechanism such as described and shown, the material is conveyed up the slope in bulk irrespective of fluctuations in the time of its arrival at the slope bottom, and all handling of cars on the slope and at the slope head is avoided. Furthermore coal may be simultaneously delivered to the conveyor from a plurality of levels, or from a plurality of sides of one level simultaneously, and without being interfered with by such delivery from other levels. Also there is effected the saving of time necessary in making up slope trains at the top and bottom, and the necessity of signaling from the bottom to the engine room at the top is avoided as well as avoiding many other disadvantages incident to the usual installations. There is also avoidance of the length limitations and excessive cost and wear of conveyor belt hoisting installations such as are sometimes used for work of this kind.

In Figs. 11 and 12 a somewhat different form of driving mechanism for the reciprocating conduit is shown. In said form a cross rod 78 is fixed to the bottom frame reaches 13 and 14 of one of the conveyor sections. Fixed to the rod 78 is an endless sprocket chain 79 running over idler sprockets 80 and 81, and also over a driven sprocket 82. Sprockets 80 and 81 are journaled in a suitable manner not shown. Sprocket wheel 82 is mounted in journal bearings 83 and 84, and fixed to the shaft of sprocket wheel 82 is a bevel gear 85.

A reversible drive for bevel gear 85, as embodied, comprises two bevel gears 86 and 87, fixed to a shaft 88, and slideable alternatively into and out of engagement with the bevel gear 85. Shaft 88 is slideable in bearings 89, 91 and 92. Splined on shaft 88 is a gear wheel 93, with which wheel meshes a pinion 94 fixed on the shaft of a motor 95. Thus gear wheel 93 and shaft 88 and bevel pinions 86 and 87 rotate together, but shaft 88 and bevel pinions 86 and 87 are slideable relatively to gear wheel 93.

The embodied means for sliding shaft 88 to and fro from time to time and thereby reversing the drive on the conduit, comprises two arms 96 and 97 fixed at proper points on the conduit and adapted respectively to engage the opposite ends of the shaft 88 and thus to move it longitudinally.

As the conduit approaches one end of its path of travel, the arm 96 will slide the

shaft 88 into the position shown in Fig. 12, and bevel gear 86 will drive sprocket wheel 82 and sprocket chain 79 in one direction, thereby moving the conduit in one direction. When the opposite end of the path of travel of the conduit has been reached arm 97 will engage the end of shaft 88, slide it longitudinally and thereby move bevel gear 86 out of mesh with gear 85, and will move bevel gear 87 into mesh with bevel gear 85. This will reverse the movement of sprocket wheel 82 and sprocket chain 79, and will thereby travel the conduit 1 in the opposite direction.

Means are provided for holding the shaft 88 at either end of its travel but permitting it to be shifted from one end to the other as just described. As embodied, a bevel roller 98 is loosely and rotatably mounted upon shaft 88 between collars 99 and 100 fixed to the shaft. Bearing on the roller 98 is a pointed plunger 101, which is mounted on a rod 102. Rod 102 is longitudinally slideable in supports 103 and 104, and is yieldingly impelled against the roller 98 by a coiled spring 105. When shaft 88 is pushed longitudinally, plunger 101 will yield, and when roller 98 has passed, the plunger will lock on the other side thereof until the shaft is again moved by one of the arms 96 or 97. Thus accidental play of the shaft is prevented, while it is free to perform its regular movement.

In Fig. 13 is shown in elevation and somewhat diagrammatically an embodiment of the invention adapted to convey material downwardly on a gradient, or incline, and in connection therewith mechanism and arrangements whereby a portion of the material in one part of the mechanism will act by its weight to perform work on another portion of the mechanism and vice versa in the other direction. In Fig. 13 the conduit is shown in two parts 110 and 111, the part 110 moving upwardly when the part 111 is moving downwardly and vice versa. The part 110 empties its end section into the part 111 at each reciprocation, and owing to the fact that one of the parts 110 and 111 is going up while the other is going down, the weight of both the mechanism and the material in one section is employed against the work of merely raising the mechanism in the other section, while the material therein is held at rest by the blades 35, to effect the travel between the material and the conduit as already described.

In Fig. 14 a somewhat different form of mechanism, but operating very much in the same manner, is provided. In this particular form, however, the two parts 112 and 113 (corresponding to the parts 110 and 111, already described so far as general operation is concerned) have their adjacent ends telescoping. There is thus secured the working

of the weight of the descending mechanism and material of one part 112 or 113 against the raising of the mechanism of the other part. The mechanical saving or economy in 5 an actual installation of large size amounts to nearly ninety per cent of the power required where there is not this cooperation just described.

In Figs. 15 and 16 are shown certain details of the telescoping ends of the conveyor parts 112 and 113. As embodied, the last regular or standard section of the part 112 is provided with an extension 115, of similar shape and general dimensions, but fitting 15 slidably within the uppermost or end section 116 of the part 113 of the conduit. The section 115 will be slightly greater in length than the total distance of separation of the two conduit parts 112 and 113 when 20 they are farthest apart.

To ease the action between the parts, section 115 is preferably supported so as to have close clearance within the section 116. As provided, the upper edge of each side 25 wall of the section 116 is turned over as shown at 118, and may be provided with an internal reinforcing strip 119, to make a rigid trackway or sliding guide and support for the section 115. The upper side 30 edges of the section 115 extend above and over the top edges 118 of the sides of the section 116, and these side top edges of section 115 are bent or arched, as shown at 120, to inclose and to provide journals for a 35 series of rollers 121, which rollers run on the edges 118 of section 116. The pintles of the rollers 121 may have bearing blocks 122 and 123 fixed to the walls of the section 115 as shown in Fig. 15. If desired also a 40 supporting roller 124 may be provided beneath the section 115.

As the parts 112 and 113 move toward and from each other, the section 115 will be supported by the series of rollers 121 running 45 on the edges 118 of section 116, at either side, the rollers running along the top edges 118 of the side walls of section 116 as upon a track. The action of the descending loose material in one of the parts 50 112 and 113 in assisting to raise or move upwardly the mechanism of the other conveyor part 112 or 113 while the material is at rest therein has already been described in connection with Fig. 13.

In Fig. 17 is shown one form of mechanism for moving the two conduit parts as shown in Figs. 13 and 14 in opposite directions. As embodied, a cross rod 130 is fixed to one of the bottom frames of the conveyor part 113, and a cross rod 132 is fixed to a bottom frame 133 of the part 112 of the conduit system. Cross rod 130 is pivotally connected by a connecting rod 134 to a wrist pin 135 fixed to an endless sprocket 65 chain 136. Cross rod 132 is pivotally con-

nected by a connecting rod 137 to a wrist pin 138 likewise fixed to the sprocket chain 136. Sprocket chain 136 runs over idler or guiding sprocket wheels 139 and 140, which are journaled in suitable bearings.

The embodied form of driving means for the sprocket chain 36 comprises an external driving sprocket wheel 142 working against a holding or bearing plate 149, operating from the other side of the chain 136 to hold the chain to the driving wheel 142. Fixed on shaft 143 of sprocket wheel 142 is a gear wheel 144. Meshing with the gear wheel 144 is a pinion 145, which is fixed on the shaft of a motor 146. Bearing and guiding plates 147 and 148 serve to hold the chain 136 to its path. By the mechanism just described, it will be seen that the conduit parts 110 and 111, or conduit parts 112 and 113, are drawn first towards each other and then 70 away from each other along their pathway 75 in the manner and with the effect and for the purpose already described. That is, in the descending part, say part 113, the material and conveyor mechanism are traveling downwardly together, while in the ascending part, which in this case would be part 112, the mechanism alone is ascending, while the material is held against upward movement by the blades 35. Thus the 80 weight of the material traveling downwardly in part 113 is utilized to reduce the work of raising the mechanism of part 112 while the material in part 112 is held at 85 rest by the blades.

In Figs. 19 and 20 is shown a different form of driving mechanism for the conduit parts 110 and 111 or conduit parts 112 and 113. In said embodiment, attached to the cross rods 130 and 132 already described is 90 a cable 155, this cable passing over a reversing sheave 156. Cable 155 is wound around a drum 157 so as to wind on and pay off equally and in either direction, dependent upon the rotation of the drum. 100 The shaft of drum 157 is journaled in bearings 158 and 159. Fixed to the shaft of drum 157 is a bevel pinion 85, corresponding to the bevel pinion 86 already described. The reversing mechanism used for the drum 110 157 may be substantially the same as that for the sprocket wheel 82 shown in Fig. 12 and already described, certain parts thereof being shown in Fig. 20 and being numbered the same as the corresponding 115 parts in Fig. 12.

In the general conveyor mechanism it will be understood that the conveyor units being attachable to and detachable from each other, and the blades being separately 125 mounted if desired, that the conveyor system is easily and rapidly extensible and contractible by units.

In Fig. 21 the drive of Figs. 9 and 10 is shown applied to operating the balanced 130

conveyors, such as are shown in Fig. 14. This drive is an alternative for the drive shown in Fig. 17. The connecting rod 51 operates one of the conduits and a cable 162 connects from the other conduit to cross-rod 52 of connecting rod 51, passing around a sheave 163 to effect the reversal of motion. This provides a very evenly balanced drive.

The invention in its broader aspects is not limited to the specific mechanisms shown and described, but departures may be made therefrom within the scope of the accompanying claims, without departing from the principles of the invention and without sacrificing its chief advantages.

What I claim is:

1. A conveyor for loose material including in combination a reciprocable conveying conduit, another reciprocable conveying conduit in alinement therewith and adapted to travel in the opposite direction therefrom, the reciprocations of each of the conveying units being in a rectilinear path, and a telescoping section between the two conduits constituting a continuous passage for the conveyed material as the two conduits approach and recede from each other, and means for reciprocating the conduits in a rectilinear path.
2. A conveyor for loose material including in combination a reciprocable conveying conduit, another reciprocable conveying conduit in alinement therewith and adapted to travel in the opposite direction therefrom, and a telescoping section between the two conduits constituting a continuous passage for the conveyed material as the two conduits approach and recede from each other, means for reciprocating the conduits and stationary, inclined material-engaging blades located within the conveyors.
3. A conveyor for loose material including in combination a reciprocable conveying conduit, another reciprocable conveying conduit in alinement therewith and adapted to travel in the opposite direction therefrom, the reciprocations of each of the conveying units being in a rectilinear path, and a telescoping section between the two conduits constituting a continuous passage for the conveyed material as the two conduits approach and recede from each other, said telescoping section being connected to one of said conduits to reciprocate therewith, and means for reciprocating the conduits in a rectilinear path.

4. A conveyor for loose material including in combination a reciprocable conveying conduit, another reciprocable conveying conduit in alinement therewith and adapted to travel in the opposite direction therefrom, the reciprocations of each of the conveying units being in a rectilinear path, and a telescoping section between the two conduits constituting a continuous passage for the

conveyed material as the two conduits approach and recede from each other, said telescoping section being connected to one of said conduits to reciprocate therewith and being movably supported upon the other of said conduits, and means for reciprocating the conduits in a rectilinear path.

5. A conveyor for loose material including in combination a reciprocable conveying conduit, another reciprocable conveying conduit in alinement therewith and adapted to travel in the opposite direction therefrom, and a telescoping section between the two conduits constituting a continuous passage for the conveyed material as the two conduits approach and recede from each other, said telescoping section being connected to one of said conduits to reciprocate therewith and having a rolling support on the other of said conduits, and means for reciprocating the conduits.

6. A conveyor for loose material including in combination a reciprocable conveying conduit, another reciprocable conveying conduit in alinement therewith and adapted to travel in the opposite direction therefrom, both said conduits having rectilinear movement only, and a telescoping section between the two conduits constituting a continuous passage for the conveyed material as the two conduits approach and recede from each other, the telescoping section being movably supported on the upper longitudinal edges of one of the conduits, and means for reciprocating the conduits.

7. A conveyor for loose material including in combination a reciprocable conveying conduit, another reciprocable conveying conduit in alinement therewith and adapted to travel in the opposite direction therefrom, both said conduits having rectilinear movement only, and a telescoping section between the two conduits constituting a continuous passage for the conveyed material as the two conduits approach and recede from each other, means for reciprocating the conduits, and stationary, inclined material-engaging blades located within the conveyors.

8. A conveyor for loose material including in combination a reciprocable conveying conduit, another reciprocable conveying conduit in alinement therewith and adapted to travel in the opposite direction therefrom, both said conduits having rectilinear movement only, and a telescoping section between the two conduits constituting a continuous passage for the conveyed material as the two conduits approach and recede from each other, said telescoping section being connected to one of said conduits to reciprocate therewith, and being mounted for rolling engagement along the upper longitudinal edges of the other conduit, and means for reciprocating the conduits.

9. A conveyor for loose material including

- in combination a trackway, a conveying conduit mounted on wheels rolling along said trackway, another conveying conduit mounted on wheels rolling along said trackway, 5 means for reciprocating said two conduits simultaneously in opposite directions along the trackway, and a telescoping section continuously joining said sections to maintain the continuity of the conveyor as the two 10 conduits alternately approach and recede from each other.
10. A conveyor for loose material including in combination a trackway, a conveying conduit mounted on wheels rolling along 15 said trackway, another conveying conduit mounted on wheels rolling along said trackway, means for reciprocating said two conduits simultaneously in opposite directions along the trackway, and a telescoping section continuously joining said sections to maintain the continuity of the conveyor as the two conduits alternately approach and recede from each other, and stationary, inclined, pivoted blades within each of said 20 conduits.
11. A conveyor for loose material including in combination a trackway, a conveying conduit mounted on wheels rolling along said trackway, another conveying conduit 25 mounted on wheels rolling along said trackway, means for reciprocating said two conduits simultaneously in opposite directions along the trackway, and a telescoping section fixed to one of said conduits and slidably supported by the other of said conduits, continuously joining said sections to maintain the continuity of the conveyor as the two conduits alternately approach and recede from each other.
- 40 12. A conveyor for loose material including in combination a trackway, a conduit reciprocable along said trackway and consisting of a plurality of units, said units having frames underneath, and having bottoms and sides but no ends mounted on the frame, wheels attached to the frame and rolling upon the track, and inclined material engaging blades located between the sides of the conduit.
- 50 13. A conveyor for loose material including in combination a trackway, a conduit reciprocable along said trackway and consisting of a plurality of units, said units having frames underneath, and having bottoms and sides but no ends mounted on the frame, wheels attached to the frame and rolling upon the track, means for attaching the frames of contiguous units together, and inclined material engaging blades located between the sides of the conduit.
- 60 14. A conveyor for loose material including in combination a trackway, a conduit reciprocable along said trackway and consisting of a plurality of units, said units having frames underneath, and having bot-
- toms and sides but no ends mounted on the frame, wheels attached to the frame and rolling upon the track, means for attaching the frames of contiguous units together, means attached to one of said unit frames 70 for reciprocating the conduit along the trackway, and inclined material engaging blades located between the sides of the conduit.
15. A conveyor for loose material including in combination two inclined conduits, common means for longitudinally reciprocating said conduits simultaneously in opposite directions and means for preventing the material in the ascending conduit moving 75 upwardly with the conduit.
16. A conveyor for loose material including in combination two inclined conduits, one arranged longitudinally above the other, the upper conduit emptying the loose material into the lower conduit, common means for longitudinally reciprocating said conduits simultaneously in opposite directions and means for preventing the material in the ascending conduit moving 80 upwardly with the conduit.
17. A conveyor for loose material including in combination two inclined conduits, the two conduits being longitudinally in alinement, the upper conduit emptying into 85 the lower conduit, common means for longitudinally reciprocating said conduits simultaneously in opposite directions and means for preventing the material in the ascending conduit moving 90 upwardly with the conduit.
18. A conveyor for loose material including in combination two inclined conduits, one arranged longitudinally above the other, common means for longitudinally reciprocating said conduits simultaneously in opposite directions and means for preventing the material in the ascending conduit moving 105 upwardly with the conduit.
19. A conveyor for loose material including in combination two inclined conduits, the two conduits being longitudinally in alinement, common means for longitudinally reciprocating said conduits simultaneously in opposite directions and means for preventing the material in the ascending conduit moving 110 upwardly with the conduit.
20. A conveyer for loose materials, comprising in combination, two telescoping trough sections, means for reciprocating the two trough sections in opposite directions in a rectilinear path, and a plurality of material engaging blades positioned between the side walls of the trough, each blade being pivoted on a pivot which is fixed with respect to the trough, the distance between a pair of adjacent pivots being less than the amplitude of the movement of the trough sections.
21. A conveyer for loose materials, com-

prising in combination two telescoping trough sections, one section being provided with rollers rolling on the upper longitudinal edges of the other section, means for reciprocating the two trough sections in opposite directions in a rectilinear path, and a plurality of material engaging blades positioned between the side walls of the

trough, each blade being pivoted on a pivot which is fixed with respect to the trough, 10 the distance between a pair of adjacent pivots being less than the amplitude of the movement of the trough sections.

In testimony whereof, I have signed my name to this specification.

KENNETH DAVIS.
